UNITED STATES PATENT OFFICE.

CHRISTIAN A. SAHM, OF INDIANAPOLIS, INDIANA.

BELT-SKIVER.

1,076,913.

Specification of Letters Patent.

Patented Oct. 28, 1913.

Application filed August 24, 1912. Serial No. 716,928.

To all whom it may concern:

Be it known that I, CHRISTIAN A. SAHM, a citizen of the United States, residing at Indianapolis, in the county of Marion and State of Indiana, have invented a new and useful Belt-Skiver, of which the following is a specification.

In the production of leather belting, especially of the heavier larger belts, it is essential that accurately and finely beveled ends be provided so that the thickness of the completed belt may be uniform and the object of my present invention is to produce a machine capable of properly beveling the ends of the belting sections at a rapid rate.

The accompanying drawings illustrate my invention.

Figure 1 is a side elevation of the complete machine; Fig. 2 a plan; Fig. 3 a fragmentary vertical section parallel with the plane of Fig. 1 and on a larger scale; Fig. 4 a plan of the work table and adjacent parts; Fig. 5 an enlarged fragmentary section transverse to the plane of Fig. 1; Fig. 6 a fragmentary detail showing the arrangement of the splitting knife and feed rolls; and Fig. 7 a fragmentary section of a slight modification.

In the drawings, 10 indicates the main frame carrying at one edge an angle iron 11 which may be vertically adjusted by temper screws 12 and clamped in adjusted position by clamping bolts 13. Secured to the upper face of iron 11 is a flexible plate 14 (conveniently a piece of saw blade steel) one edge of which projects beyond iron 11 and has secured to it one edge of the work table 15. Table 15 is further supported, at its end adjacent the plate 14, by a temper screw 16. Adjacent its delivery edge table 15 carries a feed roll 17, the periphery of which is preferably slightly roughened. Roller 17 is journaled in suitable bearings carried by the table 15 and at one end is provided with a worm wheel 18 which meshes with a worm 19 carried by a shaft 20 journaled in suitable bearings on the under side of table 15. Shaft 20 is provided with a sprocket wheel 21 connected by a chain 22 with a suitable main driving shaft 23. Table 15 at its edge opposite the plate 14 is provided with an extending arm 25 to which is connected a rod 26 extending up through the frame 10 and engaged by a spring 27 which normally urges the free edge of the table 15 upwardly.

Mounted upon the upper face of frame 10

is a clamp 31 in which is mounted a sliding bar 32 which may be clamped in any desired longitudinal position by the clamping bolts 33. Rod 32 carries two vertically adjustable yokes 34 and 35 which support bearings 36 and 37 respectively for the ends of a pressure roller 38 which is arranged immediately above the feed roller 17. Yoke 34 is vertically adjustable by any suitable adjusting means such as temper screw 39 and the lifting spring 39' so that the adjacent end of roller 38 may occupy an accurate position relative to the cutting edge of a splitting knife 41 which is arranged within the delivery crotch between rollers 17 and 38, as is clearly shown in Fig. 5. The opposite end of roller 38 is normally urged downwardly by any suitable means acting upon yoke 35. In Fig. 1 I show a weighted lever 42 acting upon said yoke while in Fig. 7 I show a compression spring 43 acting upon said yoke. The main body of the belt section 51 may be supported upon a side table 52.

In operation, roller 17 is adjusted, by means of the temper screws 12 and 16 until its lefthand end (Figs. 1, 3, and 6) comes just into the plane of the cutting edge of the knife 41 and yoke 34 is adjusted until the righthand end of the roller 38 comes down just into the cutting plane. Bar 32 is then adjusted longitudinally until the righthand end of the roller 38 is spaced from the lefthand end of roller 17 by a distance equal to the length of the desired bevel to be cut upon the end of the belt 51. Thereupon the parts are put in motion and the end of the belt fed through between the rollers 17 and 38 as shown in Fig. 6, the knife serving to slice the belt and to remove from it a wedge shaped piece 55. It will be noticed that so long as the lefthand end of roller 17 and the righthand end of roller 38 are properly adjusted in the manner set forth, any desired angle and length of bevel may be obtained without any other adjustment of the parts, the work table and pressure roller yielding properly in opposite directions to accommodate belting of different thicknesses. As a consequence a very considerably increased amount of work may be produced by a manipulation of the machine.

I claim as my invention:

1. A machine for scarfing belting, comprising a cutting knife, a work table arranged upon one side of the cutting plane,

of said knife, a roller carried by said work table, means for yieldingly swinging one end of said roller toward the cutting plane, a second roller arranged above and overlapping the first roller, means for adjusting said second roller axially relative to the first roller, means for swinging toward the cutting plane that end of the second roller which lies farthest from the swinging end 10 of the first roller, and means for driving one of said rollers.

2. A machine for scarfing belting, comprising a cutting knife, a work table arranged upon one side of the cutting plane 15 of said knife, a roller carried by said work table, means for yieldingly swinging one end of said roller toward the cutting plane, a second roller arranged above and overlapping the first roller, means for swinging 20 toward the cutting plane that end of the second roller which lies farthest from the swinging end of the first roller, and means for driving one of said rollers.

3. A machine for scarfing belting, comprising a feed roller, a pressure roller, a knife arranged in the delivery crotch between said rollers, means for independently adjusting one pair of opposite ends of said two rollers toward and from the plane of 25 the knife, and means for permitting yielding of the other pair of opposite ends of said rollers relative to the plane of the knife.

4. A machine for scarfing belting, comprising a feed roller, a pressure roller, a knife arranged in the delivery crotch between said rollers, means for independently 30 adjusting one pair of opposite ends of said two rollers toward and from the plane of the knife.

the knife, means for permitting yielding of 40 the other pair of opposite ends of said rollers relative to the plane of the knife, and means for adjusting said two rollers axially relatively to each other so that they may be made to overlap to a greater or less extent. 45

5. A machine for scarfing belting, comprising a feed roller, a pressure roller, a knife arranged in the delivery crotch between said rollers, means for independently 50 adjusting one pair of opposite ends of said two rollers toward and from the plane of the knife, and adjustable means for permitting yielding of the other pair of opposite ends of said rollers relative to the plane of the knife. 55

6. A machine for scarfing belting, comprising a feed roller, a pressure roller, a knife arranged in the delivery crotch between said rollers, means for independently 60 adjusting one pair of opposite ends of said two rollers toward and from the plane of the knife, means for permitting yielding of the other pair of opposite ends of said rollers relative to the plane of the knife, and means for adjusting said two rollers axially 65 relatively to each other so that they may be made to overlap to a greater or less extent, the overlapping ends of said rollers being the ones which are adjustable relatively to the plane of the knife. 70

In witness whereof, I, have hereunto set my hand and seal at Indianapolis, Indiana, this 17th day of August, A. D. one thousand nine hundred and twelve.

CHRISTIAN A. SAHM. [L.S.]
